UNITED STATES PATENT OFFICE.

FRANK LESLIE CUNNINGHAM, OF CALGARY, ALBERTA, CANADA.

MOP-CLOTH HOLDER.

Application filed September 21, 1922. Serial No. 589,633.

To all whom it may concern:

Be it known that I, FRANK LESLIE CUNNINGHAM, a subject of the King of Great Britain and Ireland, and residing at 207 Alberta Corner, in the city of Calgary, Province of Alberta, Dominion of Canada, having invented certain new and useful Improvements in a Mop-Cloth Holder, do hereby declare the following to be a full, clear, and exact description of the same.

My invention relates to improvements in a mop cloth holder in which it is sought to grip the mop cloths so as to prevent movement thereof, the gripping members being such that they will assist the passage of a wringer over the head of the cloth.

These objects I accomplish with the device illustrated in the accompanying drawings in which—

Fig. 1 is a perspective view of the front of the holder showing in dotted lines the securing plate in the open position for placing the mop cloth.

Fig. 2 is a side elevation showing in dotted lines the mop cloth in place.

Similar letters refer to similar parts throughout the several views:

A base plate *a*, has formed thereon at one end a handle socket *b*, which socket is adapted to receive a handle. The lower end of the base plate is recessed and has the interior surface of the recess splayed outwardly from the surfaces of the base plate as shown at *c*. These splayed surfaces assist a wringer member to pass from the base plate on to the mop cloth as the outer edges of the splayed members rest upon the cloth. Pinned upon the base plate

adjacent the splayed portion is a clamping plate *d*, the pinned joint on one side 40 of the base plate being in a slot *e*, and on the other side being detachable as shown at *f*.

It will be seen that the clamping plate *d*, may be released from the base plate 45 *a*, on one side only as shown at *f*, and will pivot in the slot *e*, to the other side. By this means access is obtained to the recess in the base plate and the cloth *g*, may be readily placed therein. Once the cloth is 50 placed in the slot recess and the clamping member *d* is fastened to the plate *a*, the cloth is held by contact between the lower edges of the splayed surfaces *c*, and the inner edge of the plate *d*.

Having thus described my invention what I claim is:

A mop holder comprising a plate provided with a handle receiving socket at one end thereof, the opposite end of said plate being provided with a rectangular recess, said plate being provided with a plurality of slits extending into said recess, and the alternative portions of the plate between said slits being bent forwardly and rearwardly to form a jaw, a clamping jaw pivoted to the portion of said plate forming one side of the recess, and means carried by the portion of the plate forming the other side of the recess for detachably retaining said pivoted jaw in clamping position.

FRANK LESLIE CUNNINGHAM.
